UNITED STATES PATENT OFFICE.

CHARLES V. KAHOA, OF RUSSELL, IOWA, ASSIGNOR OF ONE-HALF TO C. N. RUARK, OF SAME PLACE.

MACHINE FOR MAKING WIRE FENCES.

SPECIFICATION forming part of Letters Patent No. 679,969, dated August 6, 1901.

Application filed November 23, 1900. Serial No. 37,443. (No model.)

To all whom it may concern:

Be it known that I, CHARLES V. KAHOA, a citizen of the United States, residing at Russell, in the county of Lucas and State of Iowa, 5 have invented a new and useful Machine for Making Wire Fences, of which the following is a specification.

My object is to provide a simple, strong, and durable machine adapted to be manually 10 operated for fixing cross-wires to fence-wires that are stretched between and fixed to a line of fence-posts in such a manner that the cross-wires will serve as stays for the fixed fence-wires and also in such a manner that 15 the cross-wire may be continuous and extend up and down at close intervals as required to produce a woven-wire fence.

My invention consists in the construction, arrangement, and combination of operative 20 mechanisms with a frame having a handle, as hereinafter set forth; pointed out in my claims, and illustrated in the accompanying drawings, in which—

Figure 1 is a side view of the machine, and 25 Fig. 2 an edge view showing the relative positions of all the operative parts connected with the frame. Fig. 3 is a transverse sectional view on the line $x-x$ of Fig. 1, showing 30 a detent for retaining the crank and rotatable wheels stationary. Fig. 4 is a perspective view of the spool for holding wire detached from the machine.

The letter A designates the two mating metal parts of the frame jointly fixed by 35 means of rivets or in any suitable way to a wooden handle B in such a manner that they will extend in parallel position. Between the mating parts of the frame are mating gear-wheels C and D, journaled thereto and in 40 mesh with each other. To the axle of the wheel C a crank-handle F is applied, as required for rotating the wheels. The ends of the mating parts A of the frame are bifurcated and a gear-wheel H, corresponding in 45 size with the wheels C and D, has a tubular hub H^2 , that is fitted in corresponding bearings in the bifurcated end portions of the mating parts of the frame and the ends of the hub project on each side of the frame. 50 The wheel and hub are slotted, so that when properly adjusted, as shown in Fig. 1, the

end of the frame and the wheel H and its hollow hub H^2 can be placed astride of a fixed fence-wire and the slotted hub and wheel rotated as required to coil a stay-wire on the 55 fence-wire.

J is a spool mounted in a wire frame J^2 , adapted to be detachably connected to the hub H^2 by means of pins K, as shown in Fig. 2, in such a manner that when the hub H^2 is 60 rotated, wire will be drawn from the spool and coiled on the fence-wire that extends through the hub.

m is a wire frame that has eyes at its ends and is detachably fastened on the end of the 65 hub by means of a pin m' to extend transversely through coinciding pin-holes in the hub. Coinciding notches in the edge of the hub admit the wire frame to aid in retaining said frame stationary and as required to aid 70 in coiling the wire that comes from the spool around a fence-wire that extends longitudinally through the hub.

N is a stud projecting from the face of one of the parts A of the frame. It has a slot in 75 its free end to admit the end of the wire on the spool and serve as a means of fastening the end of the wire, as indicated by dotted lines in Figs. 1 and 2.

P is a detent in the form of a wire frame 80 fixed to the frame, as shown in Fig. 3, or in any suitable way, so that it will retain the handle-crank F in proper position to keep the slotted wheel H and hub H^2 in position, as shown in Fig. 1 and as required for placing 85 the machine on and off a fixed fence-wire.

Dowel-pins r, fixed in the end of the hub H^2 , are adapted to enter corresponding pin-holes in the end of the spool J to aid in retaining the spool connected with the end of 90 the hub, as indicated in Fig. 2 and as required for using the machine to bind wire on the spool. A pin or bolt s extends through the spool and hub and is fastened by means of a key s' and aids in retaining the spool in 95 alinement with the hub when the spool and hub are jointly rotated for winding wire on the spool.

Having thus described the purpose of my invention and the construction, functions, arrangement, and combination of all the parts, the practical operation and utility of the ma- 100

chine will be readily understood by persons familiar with the art to which it pertains, and

What I claim as new, and desire to secure 5 by Letters Patent, is—

1. In a machine for fixing cross-wires to fence-wires, a frame composed of two mating parts fixed to a handle to extend in parallel position and the ends of said mating parts 10 bifurcated, and a gear-wheel having a tubular hub and coinciding slots in the wheel and hub to admit a fence-wire, two mating gear-wheels journaled in the frame below the wheel having the tubular hub, a crank-handle on the 15 axle of the lower gear-wheel, and a wire frame fixed across the lower end of the frame to engage the crank-handle, arranged and combined to operate in the manner set forth for the purposes stated.
2. In a machine for fixing cross-wires to fence-wires, a wheel having a tubular hub and coinciding slots in the wheel and hub, a wire frame adapted to be detachably fastened to one end of the hub by means of pins, and 25 a spool mounted in said wire frame, arranged and combined to operate in the manner set forth for the purposes stated.
3. In a machine for fixing cross-wires to fence-wires, a wheel having a tubular hub 30 and coinciding slots in the wheel and hub, a wire frame adapted to be detachably fastened to one end of the hub by means of pins, a

spool mounted in said wire frame, and means for coiling the wire that extends from the spool longitudinally through the hub around 35 a fence-wire also extended longitudinally through the hub, arranged and combined to operate in the manner set forth for the purposes stated.

4. A machine for fixing cross-wires to fixed fence-wires, comprising a frame composed of two mating parts fixed to a handle to extend in parallel position therefrom and in alignment therewith, the ends of said mating parts bifurcated, three gear-wheels mounted between the mating parts of said frame, the wheel nearest the handle provided with a crank-handle, a detent on the lower end of the frame for holding the crank-handle, the wheel at the bifurcated ends provided with 45 a tubular hub, coinciding slots in said wheel and hub to admit a fence-wire, a frame adapted to be detachably fastened to one end of said hub, means for fastening said frame to the hub, a spool mounted on said frame and 50 means fixed in said hub for coiling the cross-wire around the fence-wire, arranged and combined to operate in the manner set forth for the purposes stated.
